UNITED STATES PATENT OFFICE

162,809

ARTICLE DISPENSING CABINET OR THE LIKE

Fred N. Gay, near Seattle, Wash.

Application December 3, 1948, Serial No. 149,935

Term of patent 14 years

(Cl. D80—11)

To all whom it may concern:

Be it known that I, Fred N. Gay, a citizen of the United States of America, residing near Seattle, in the county of King and State of Washington, have invented a new, original, and ornamental Design for an Article Dispensing Cabinet or the like, of which the following is a specification, reference being had to the accompanying drawing, forming part thereof.

I claim:

The ornamental design for an article dispensing cabinet or the like, as shown.

FRED N. GAY.
